(57) **CLAIM**

The ornamental design for a cup lid, as shown and described.

DESCRIPTION

FIG. 1 is a perspective view of a first embodiment of a cup lid; FIG. 2 is a top plan view of the cup lid of FIG. 1;

FIG. 3 is a bottom plan view of the cup lid of FIG. 1;

FIG. 4 is a front view of the cup lid of FIG. 1;

FIG. 5 is a back view of the cup lid of FIG. 1;

FIG. 6 is a right side view of the cup lid of FIG. 1;

FIG. 7 is a left side view of the cup lid of FIG. 1;

FIG. 8 is a perspective view of a second embodiment of the cup lid;

FIG. 9 is a top plan view of the cup lid of FIG. 8;

FIG. 10 is a bottom plan view of the cup lid of FIG. 8;

FIG. 11 is a front view of the cup lid of FIG. 8;

FIG. 12 is a back view of the cup lid of FIG. 8;

FIG. 13 is a right side view of the cup lid of FIG. 8;

FIG. 14 is a left side view of the cup lid of FIG. 8;

FIG. 15 is a perspective view of a third embodiment of the cup lid;

FIG. 16 is a top plan view of the cup lid of FIG. 15;

FIG. 17 is a bottom plan view of the cup lid of FIG. 15;

FIG. 18 is a front view of the cup lid of FIG. 15;

FIG. 19 is a right side view of the cup lid of FIG. 15;

FIG. 20 is a left side view of the cup lid of FIG. 15; and,

FIG. 21 is a back view of the cup lid of FIG. 15.

In the drawings, the broken lines depict unclaimed environmental subject matter only and form no part of the claimed design.

1 Claim, 14 Drawing Sheets
